UNITED STATES PATENT OFFICE.

BENJAMIN H. DIETZ AND ALBERT E. HANSEN, OF CHICAGO, ILLINOIS.

FORMING APPARATUS FOR WOOD VENEER STRIPS OR BANDS.

Application filed May 28, 1923. Serial No. 641,901.

To all whom it may concern:

Be it known that we, BENJAMIN H. DIETZ and ALBERT E. HANSEN, citizens of the United States, and residents of Chicago, county of Cook, and State of Illinois, have invented certain new and useful Improvements in Forming Apparatus for Wood Veneer Strips or Bands; and we hereby declare that the following is a full, clear, and 10 exact description thereof, reference being had to the accompanying drawings, and to the letters of reference marked thereon, which form a part of this specification.

This invention relates to improvements in forming apparatus for wood veneer strips and consists of the matters hereinafter described and more particularly pointed out in the appended claims.

One of the objects of the present invention is to provide a simple and efficient apparatus of the kind above mentioned for bending and forming a band, comprising a plurality of glued veneer strips into the desired shape, and for holding it under pressure until it sets, so that it thereafter maintains the shape or form imparted to it by the apparatus.

Another object of the invention is to provide in such an apparatus, removable, coacting form members or cores between which the glued veneer strips are bent into shape and are permitted to "set" after said cores have been locked together and have been removed from the apparatus so that the said apparatus may be again used in bending the next band in the same manner, while the first band is drying and setting.

A further object of the invention is to so construct the apparatus that it is particularly adapted for bending and forming bands into shapes having reversely curved parts, as for instance the side bands of "grand" piano bodies and the like.

These objects of the invention as well as the several advantages of the invention will more fully appear as we proceed with our specification.

In the drawings:

Fig. 1 is a view in side elevation of an apparatus embodying our invention, for bending and forming glued veneer strips into bands.

Fig. 2 is a view partly in end elevation and partly in vertical section on an enlarged scale, of our improved apparatus, the plane

of the section being taken on the line 2—2 of Fig. 1.

Figs. 3 and 4 are vertical sectional views through the apparatus, on the lines 3—3 and 4—4 respectively of Fig. 1.

Fig. 5 is a view partly in side elevation and partly in vertical longitudinal section, with the parts in a position different from that shown in Fig. 1.

Fig. 6 is a view of the two coacting members providing the form or core, with a formed band locked therein, and after the core has been removed from the apparatus.

Fig. 7 is a detail vertical sectional view taken on the line 7—7 of Fig. 5.

Fig. 8 is a detail vertical sectional view taken on the line 8—8 of Fig. 1.

Fig. 9 is a plan view of a band, formed by our improved apparatus.

Fig. 10 is a perspective view of a bar forming a part of our improved apparatus.

Fig. 11 is a view in elevation of one of a plurality of links for locking the two parts of the form or core together.

Our improved apparatus is illustrated herein as of the horizontal type and will be described as such, but as will be apparent, the same principles of construction and operation may be embodied in an apparatus of the vertical type without departing from the spirit of the invention.

In general our improved apparatus includes a male form block and a female form block which are mounted for a relative movement toward and away from each other. Associated with said form blocks are form or core members which are detachably and removably mounted on the form blocks. The veneer strips to form the band are laid the one upon the other and are glued together while upon one core member, after which a relative movement between the form blocks is produced to bring the other core member into engagement under pressure with the built up strips on the first core member. Both core members are unlocked from the form blocks and then locked together with the formed band between them.

The core members, with the band between them, are then removed from the apparatus and placed to one side to permit the band to set and dry, the apparatus being ready for the forming of the next band in the same manner, while the first band is setting and drying.

Referring now in detail to that embodiment of the invention illustrated in the accompanying drawings:—15 indicates as a whole the frame of our improved apparatus 5 which is mounted upon a floor, platform or like support 16. Said frame has upright, spaced, end standards 17 and 18 which are connected together at their top and bottom ends by suitable front and rear, horizontal 10 connecting rods 19—19, and surrounding said rods between said standards are tubes 20—20 which hold the standards in the desired spaced relation. To assist in rigidly holding the frame against distortion, we provide outwardly and downwardly inclined, adjustable brace rods 21—21 which connects the top ends of the standards 17 and 18 with the support 16 at points spaced from the bottom ends of said standards, said 20 bottom ends being also secured to said support by outwardly extending L shaped brackets 22.

The end standard 17 is preferably made of channel bars arranged in front and rear, 25 transversely spaced pairs 17^a—17^a, with the channel bars of each pair spaced from each other and with the flanges of the channel bars of each pair, facing away from each other, (see Fig. 4). The top and bottom 30 ends of each pair of channel bars are connected together by transverse plates 23—23 and at points between said ends said channel bars are further connected by transverse bolts and spacer tubes 24.

35 The end standard 18 is also preferably made of channel bars arranged in front and rear, transversely spaced pairs 18^a—18^a with the channel bar of each pair spaced from each other and with the flanges of the channel bars of each pair facing away from each other. The top ends of both pairs of channel bars 18^a—18^a are connected together by means of elongated rectangular blocks 40—26 arranged on opposite sides of the standard. The bottom ends of the pairs of standards 18^a—18^a are connected together by a transverse plate 27 on the inside of the channel bars and a transverse elongated rectangular block 28 on the outside of said 45 angle bars. At points between said top and bottom ends said channel bars are further connected by transverse bolts and spacer tubes 29—29.

55 The bottom plate 23 of the standard 17 and the bottom plate 27 of the standard 18 are connected together by longitudinal extending pairs of channel bars 30—30 respectively, (see Figs. 3, 4, 5) arranged in planes between the longitudinal rods 19. 60 The angle bars of each pair have their flanges directed outwardly and connecting the top flange of each pair are longitudinal plates 31—31 which provide tracks or rails as will hereinafter appear.

65 32—32 indicate longitudinally extending

bottom and top guide bars which connect the standards 17—18 together in the plane of the rods 19—19. Each guide rod 32—32 extends at its ends through plates 33 which bind together the channel bars of each pair 70 17^a—18^a of the standards 17—18, there being suitable nuts on the ends of said rods 32 outside of the standards. It is apparent from the construction just described that the frame 15 as a whole is strong and rigid and 75 is capable of withstanding the pressures imposed upon it in the use of the apparatus.

On the inside of the standard 18 midway between its ends, is a horizontally disposed block 34 which constitutes the male form block of the apparatus. The top and one end of said block, as illustrated in the drawings, are of such configuration as to conform in shape to that of the body band of a "grand" piano. Said block is spaced from the standard 18 by means of transverse channels 35—35 and embedded in said block are longitudinally extending anchor bolts 36—36 arranged in the median plane of the apparatus. The ends of said anchor bolts are 80 extended through rectangular plates 37—37, which engage with the outer flanges of the inner channel bars of the pairs of bars forming the standard 18. Associated with said anchor bolts are the usual nuts, by means of 85 which the form block may be drawn up tight with respect to said standard 18 so as to be rigidly supported thereon.

The male form block 34 includes a substantially semi-cylindrical convex end 38 190 which merges into the side of the block, a quarter round convex top corner 39 which merges into the other side of the form block, and a concave and reversely curved surface 40 connecting the end and corner 38—39 respectively, together. Preferably the active surface of the male form block is covered with a strip or pad 41, such as leather.

42 indicates the female form block of the apparatus which, in this particular case, is also the movable form block. Said block is cut away at one end to conform to the associated surface or end of the male form block and includes top and bottom legs 43—44, respectively, which are adapted to embrace the top and bottom sides of the male form block 34. The cut away part of the female form block includes the concave parts 45—46 and the convex part 47 to co-operate with the parts 38, 39, 40 respectively, of the male form block. Both of the form blocks are preferably made of laminated wood so as to eliminate the tendency of said blocks to split and crack or warp out of shape. Fixed to the front and rear sides of the female form block 42 near the top and bottom thereof, are longitudinally spaced bearing sleeves 48—48 through which extend the guide rods 32, before mentioned. On the bottom surface of the female form block 42, are pro-

- vided rollers 49—49 which engage upon the rails or tracks provided by the channel bars and plates 30—31 respectively. It is apparent from the foregoing construction that 5 the form block 42 moves longitudinally of the frame, toward and away from the male block 34, the female form block rolling upon the tracks and being guided thereon by the rods 32 and sleeve 48.
- 10 To prevent the legs 43—44 of the female form block from springing apart due to the vertical pressure imposed upon them in the operation of the apparatus, we connect said legs together by tie or brace rods 50. The 15 ends of said brace rods are connected to said legs by the same bolts which secure one of the bearing sleeves 48 thereto. The said rods are offset between their ends so as to be spaced a suitable distance outwardly from 20 the front and rear surface of the form blocks, and in said rods are provided turn-buckles 51 by means of which said rods may be shortened or lengthened to provide and hold the desired adjustment between said 25 legs.

Associated with the form blocks, are inner and outer form or core members, 52 and 53 respectively, which are preferably made of laminated strips of wood. The inner core member 52 is of such contour as to fit the active surface of the male form block 34 while the outer core member 53 is of such contour as to follow the active surface of the female form block 42, there being a substantially heavy metallic strap 54 interposed between the outer core member 53 and the female form block. The core members carry laterally extending threaded posts 55 and the form blocks carry similar posts 56. 40 After the core members have been applied to their associated form blocks, they are securely held in position thereon by links 57, (one of which is shown in elevation in Fig. 11) which engages upon the posts 55 and 56 of the associated core and form blocks, winged nuts 58 being threaded on the posts to lock the connecting links in place thereon.

To assist in holding the various strips from slipping in the "laying" and "glue applying" I provide means for holding one end of said bands to the top surface of the core member 52 which is as follows. Threaded through the middle of the frame cross block 25 is a substantially long vertical rod 60 55 which has a hand wheel 61 at its top end. The bottom end of said rod is rotatively connected with the middle part of a presser foot bar 62, which bar carries near its ends, vertical guide rods 63, (see Figs. 1 and 2) 60 that slide through suitable holes in the frame cross bar 25. As the various veneer strips are laid and glued, the presser foot is raised to permit the insertion of each veneer strip and is then lowered to engage and 65 clamp the same by turning the hand wheel

62 in the proper direction, as is apparent. In the building up process, the other ends of the band are bent beneath the form block 34. By this means the glued bands which would otherwise have a relative slippage, on account of the wet glue, are preliminarily held in place.

Means are also provided on one of the form blocks for securing the veneer band to be shaped and pressed, at its middle, to said form block so that the ends of said band may readily bend to assume the curvature of the core member. Preferably, and as shown herein, said means is carried on the male form block and consists of a pair of toggle bolts 64 which are arranged radially of and at an angle midway between the ends of the concave reverse curve 40. Said bolts are pivoted at one end in ears 65 fixed in the form block 34 and carry at their other ends, winged nuts 66. Associated with said bolts is a holder or clamping bar 67, (see Fig. 10) which has slots 68 at its ends to receive said bolts. The active surface of said bar is preferably covered with leather, although this is not necessary. The offset of the tie or brace rods 51 is made great enough so that in the movement of the block 42, they will freely pass the toggle bolts 64. When the toggle bolts are swung into the position shown in Fig. 1 and the clamping bar is applied, and the wing nuts are threaded upon the toggle bolts, the clamping bar will hold the band at its middle tightly upon the core, after which the presser foot 62 is loosened sufficient to allow for relative movement of the bands when the female form block is moved toward the male form block.

Any suitable means, such as hydraulic or other power means, or even hand power means may be used for moving the female form block toward and away from the male form block. We have shown and will describe herein, a simple and efficient hand power means for imparting movement to the female form block which is as follows:

70 indicates a longitudinally extending, horizontally disposed threaded rod which is operatively connected at one end to a bracket sleeve 71 on the outer end of the female form block 42 at its middle, so as to be capable of a rotative movement in said sleeve, without an endwise movement with respect thereto. Fixed to said end of said rod near the bracket 71 is a collar 72 having radially extending spoke arms 73 by means of which said rod is rotated. The other and threaded end of said rod extends through a suitable box like casing 74 which is mounted on the inner surface of the standard 17. Said casing is braced and connected to the said standard by means of transverse channel bars 75 and lag bolts 76 so as to amply withstand the pressure imposed upon it.

Within the block like casing are two blocks

77—77 which are capable of a lateral movement toward and away from each other, each block having a semi-cylindrical recess 78. Each recess is threaded to engage the 5 screw threads of the rod 70 when said blocks have been moved toward each other. Said blocks are held in place in the casing by a plate 79, (see Fig. 5) in which is provided an opening through which the rod 70 extends. 10 80—80 indicate shafts which extend transversely through the top and bottom ends of the blocks 77 to have rotative bearing in the side walls of the casing. Between their ends, said shafts are right and left hand threaded 15 to be engaged by the blocks 77—77 so that when the shafts are rotated in one direction, the blocks move toward each other to provide coacting threads for the rod and through which said rod may be threaded, 20 and when said blocks are moved away from each other, the rod is disengaged therefrom. To one end of each shaft 80, without the casing, is fixed a spur pinion 81, both of which mesh with opposite sides of another gear 82 25 fixed to a shaft 83, journaled in one end wall of the casing between the shafts 81—81. For turning the shaft 83, we provide the hand wheel 84.

With the various parts located in the position shown in Fig. 1, the hand wheel 84 is turned to bring the two blocks 77—77 together to engage the threaded rod 70 in the manner of a nut. The shaft 70 is now rotated in one direction by means of the spokes 73 and this produces a movement of the female block 52, toward the male block, the female block rolling on the tracks provided by the channels 30, and being guided in this rolling movement by the guide rods 32 and 40 ears 48. As the bottom leg of the female form approaches the free ends of the veneer strips, they are lifted upwardly toward the inner core form, which movement of the female block is continued until the top leg of 45 the female form block engages the veneer strip on the top of the inner core. At this point of movement of the female form block, it will be noticed that the band made up of the veneer strips is engaged near its two ends 50 upon the top and bottom parts of the inner core member. Further movement of the female form block is temporarily discontinued and the clamping plate 67 is removed by unscrewing the nuts 68 and swinging the toggle 55 bolts downwardly into the position shown in Fig. 5. After the clamping bar has been removed, the presser foot bar 62 is elevated to provide ample room for the final part of the 60 movement of the female form block and core member. Movement is again imparted to the female form block to bring it into the position shown in Fig. 5 where the band is held in a tight, snug engagement between the inner and outer core members.

65 The ends of the links 57 which are con-

nected to the studs 56 of the male and female form blocks are now removed therefrom by unscrewing the winged nuts 58 and said ends are then connected to the associated studs 55 on the inner and outer core bands. In making this change it is only necessary after removing the proper winged nuts to swing the links about their other ends, so that the recesses at the first named ends engage the co-acting studs of the core members after which 70 the winged nuts are threaded in place to lock the links thereon. The two members of the core are now locked together with the glued and pressed band between them, the next 75 step being the removal of the core members 80 and band from the apparatus after which it is set aside to dry.

The shaft 70 is now turned in the reverse direction and this draws the female form block away from the male block, breaking 85 the bond existing between the male form block and the outer core member and its metal backing strip 54, all of which is yet mounted on the male form block. As soon as this bond is broken to release the female 90 form block, the hand wheel 84 is turned in that direction which will impart a relative movement to the nut blocks 77 away from each other. This releases the screw threaded rod 70 from said blocks and the rod is pulled 95 through the housing to quickly return the female form block to its open, starting position, a knob or other hand hold being provided on the end of the rod for that purpose.

It is next desired to strip or remove the 100 cores from the male form block and as they were applied under great pressure, it is first necessary to break the bond formed by said pressure between the core members and the male form block. To that end I provide 105 the following:

90—90 indicates two vertical shafts which are suitably journaled in the transverse frame blocks 26—28 before mentioned, each shaft having right and left hand threads, 110 as shown in Fig. 5. To the top end of each shaft above the blocks 26 is fixed a worm gear 91 which meshes with worms 92 fixed on a transverse horizontal shaft 93. Said shaft 93 has bearing in suitable bearing blocks fixed on a plate 94 at the top end of the standard 18. To one end of the shaft 93 is fixed a hand wheel 95 for turning the same.

Associated with the upright shafts 90 are 120 two transverse blocks 96—96 which slide between the channels 18^a of the standard 18 and upright flat bars 97 fixed to the top and bottom transverse frame blocks 26—28 respectively, the blocks 96—96 having threaded holes through which the shafts 90—90 extend. Threaded through the middle of each block 96—96 is a horizontally disposed rod 98—98 and the outer end of each rod is provided with a hand wheel 99. To the 125 130

inner end of each rod 98 is suitably secured a transverse stripper bar 100—100. Each stripper bar carries guide rods 101—101 which slide through suitable openings in the blocks 96 before mentioned.

When it is desired to strip the core from the male form block 34, the hand wheel 95 is turned in one direction rotating the two upright shafts 90 in the same direction, 10 causing the blocks 96 to move, vertically upon said shafts, toward and away from each other in the guides provided by the channels 18^a and the upright bars 97. When the presser bars 100 are in the plane of the 15 ends of the core with the formed band between the members thereof, the hand wheels 99—99 are turned in one direction. This moves the rod 98 with the stripper bars 100 inwardly toward the ends of said core and 20 band and moves the same endwise of the male form block, to loosen the bond between them. The rods 98 are now rotated in the other direction retracting the stripper bars when the core with the formed band secured 25 therein is removed from the male form block in a plane at right angles to the longitudinal median line of the apparatus. The core with the band, as shown in Fig. 6, is placed in a suitable place to dry and set, when 30 other core members are inserted in place upon the form blocks and the bands applied in the manner hereinbefore described.

It is herein pointed out that each apparatus has associated with it a number of 35 core members so that as one band is formed and removed from the apparatus, another band may be started with another set of core members, so that a great saving is had in that only one apparatus is necessary for a 40 great number of bands, instead of one large form as now made for each band. Thus, the apparatus need not stand idle while each band is drying and setting, the average time allowed for drying and setting being 48 45 hours.

Furthermore, the core members with the bands therein may be easily handled and do not take up near as much storage space while 50 drying as does the ordinary frame now used in making such bands. The operation is manifest from the foregoing description.

While in describing our invention we have referred to certain details of mechanical construction and arrangement of parts, we 55 do not wish to be limited thereto except as may be pointed out in the appended claims.

We claim as our invention:

1. In an apparatus of the kind described, the combination of coacting forming blocks 60 having opposed faces of generally deep concave and high convex form with intermediate reverse curve portions, the curve of such concave and convex forming surfaces being deeper than said reverse curve by at least 65 the thickness of the band to be formed, said

concave forming block having extended parallel end portions permitting continued travel of one form block relative to the other after the engagement of the end portions of the shaping faces of both forms with the work to the depth of said reverse curve. 70

2. In an apparatus of the kind described, the combination of coacting forming blocks having opposed faces of generally deep concave and high convex form with intermediate reverse curve portions, the curve of such concave and convex forming surfaces being deeper than said reverse curve by at least 75 the thickness of the band to be formed, and means for connecting said extended parallel end portions together against spreading. 80

3. In an apparatus of the kind described, the combination of coacting forming blocks having opposed faces of generally deep concave and high convex form with intermediate reverse curve portions, the curve of such concave and convex forming surfaces being deeper than said reverse curve by at least 85 the thickness of the band to be formed, removable means for clamping the work to be formed to the reverse curve portion of said convex forming block, said concave forming block having extended parallel end portions permitting continued travel of the concave forming block with respect to said convex forming block, after the engagement of the end portions of the shaping faces by both forms with the work to the depth of said reverse curve and after said clamping means have been removed. 90

4. In an apparatus of the kind described, the combination of coacting forming blocks having opposed faces of generally deep concave and high convex form with intermediate reverse curve portions, the curve of such concave and convex forming surfaces being deeper than said reverse curve by at least 100 the thickness of the band to be formed, lining members for said forming faces, means for removably attaching said lining members to the associated blocks, said concave forming blocks having extended parallel end portions permitting continued travel of one form block relative to the other after engagement 105 of the end portions of the shaping faces of both lining members with the work to the depth of said reverse curve, said means for removably attaching said lining means being capable of being actuated to secure both 110 lining members together to hold the work between them. 115

5. In an apparatus of the kind described, the combination of a convex forming block and a concave forming block cooperable therewith and including legs adapted to straddle extensions on said first mentioned blocks and upon which said legs lay the work being formed, means connecting said legs together, and means for producing a 120 relative movement between said blocks, in 125 130

cluding devices for holding the blocks together under pressure.

6. In an apparatus of the kind described, the combination of a convex forming block 5 and a concave forming block cooperable therewith and including legs adapted to straddle extensions on said first mentioned blocks and upon which said legs lay the work being formed, brace rods including 10 turn-buckles connecting the free ends of said legs together, and means for producing a relative movement between said blocks and for holding them together under pressure.

15 7. In an apparatus of the kind described, the combination of a concave forming block and a convex forming block cooperable therewith, said blocks being capable of a relative movement toward and away from

each other and having coacting forming 20 surfaces to bring the ends of the work around parallel, lining members on said forming surfaces, said lining members being adapted to be locked together after the work has been formed, and means mounted 25 on the convex forming block to simultaneously engage both ends of said lining members for loosening the same from the forming blocks.

In testimony that we claim the foregoing 30 as our invention, we affix our signatures in the presence of two witnesses, this 26th day of May, A. D. 1923.
